UNITED STATES PATENT OFFICE

ROLLIN ABELL, OF MILTON, MASSACHUSETTS

ENGINE STARTER

Application filed February 6, 1922. Serial No. 534,355.

This invention relates to starters for internal combustion engines, and, among its objects are the following: to provide an improved construction by which the load will 5 be applied to the starting motor gradually so as to avoid sudden shock; by which the shiftable starting pinion will be shifted into gear automatically before the starting motor can accelerate appreciably; by which the 10 shifting movement of the starting pinion will be made initially slow but rapidly accelerative; and by which the end-thrust applied to the starting pinion will be diminished gradually as the pinion moves from its 15 inoperative to its operative position.

These objects cannot be attained with starters of the nut-and-screw type (which is the only automatic type heretofore recognized as possessing commercial merit) be- 20 cause cooperative screw-threads are re- stricted to a uniform lead or pitch, of what- ever steepness, throughout their range of ac- tion, and are therefore incapable of develop- 25 ing variations in end-thrust, speed of axial movement or torque. These three factors, therefore, must remain constant in a starter of the nut-and-screw type, unless some sup- plemental device is provided to modify the effects of the screw-threads.

The accompanying drawing illustrates an 30 embodiment of the invention comprising a cam arranged to shift the pinion into gear but not out of gear, a light spring being pro- 35 vided to shift the pinion out of gear at the moment of engine pick-up. This cam, by reason of certain peculiarities of shape, de- 40 velops initially slow but powerful axial movement and no appreciable torque, thus shifting the pinion into meshed relation with- 45 out turning it. Successive stages of the cam develop torque gradually but rapidly, the effective surface of the cam having a rel- 50 atively slight pitch at one portion to shift the pinion into meshing position, and a grad- ual increase of steepness to a degree within 55 the angle of repose, thus loading the start- ing motor without shock and before it has accelerated to maximum speed. An advan- 60 tage of the invention, according to the il- lustrated form of cam, is that it forms

finally a positive transmission the positive quality of which is developed gradually, and therefore without shock, during the pinion-shifting operation. For mechanical reasons this cam is preferably of duplex or twin 55 form, having two simultaneously operative cam surfaces of the same form and effect ar- ranged, diametrically opposite each other. With the construction shown all the afore- 60 said effects may be brought about in less than 65 one half of the first rotation of the starting motor, whereas commercial starters of the screw-thread type require at least one and one-half rotations to establish a starting condition. When the rapidity of acceleration 70 of an electric starting motor is considered, and when the aforesaid features of my pres- ent construction are taken into such con- sideration the advantages of such construc- 75 tion become significant.

In addition to possessing the features hereinbefore mentioned the illustrated con- struction is simpler, more durable and more reliable than any heretofore offered to the 75 trade.

Referring to the drawings,

Figure 1 is an elevation showing the starter in its normal or initial condition, and in- 80 cludes a fragment of a gear such as the fly- wheel gear of an internal combustion engine.

Figure 2 is a similar view excepting that the starter is in its operative condition and is represented partly in section.

Figure 3 is a diagrammatic view includ- 85 ing a development of the operating cam.

The following description, in so far as it deals with details of construction, is descrip- 90 tive merely of the illustrated form of device, and is not to be regarded as imposing any limitations on the scope of protection more broadly defined in the appended claims.

The rotatable shaft 10, journaled in the bearing 11, may be the rotor shaft of an 95 electric starting motor, and the bearing 11 may be formed in the casing of such motor. The casing would, as usual, provide two bear- 100 ings for the shaft. For purposes of defini- tion the shaft may be regarded as an ele- ment of the rotary operating unit hereinafter referred to. Any preferred means may be

provided to prevent axial movement of the operating unit.

A rotary and axially movable transmission unit surrounds the smooth cylindric outboard portion 12 of the shaft so as to slide thereon and be supported thereby. This transmission unit comprises a sleeve 13 on which are formed teeth to provide a starting pinion 14 for transmitting rotation to the gear 15. The latter is represented as a fly-wheel gear of an internal combustion engine. A light compression spring 16 surrounds the shaft and is sufficient to move the transmission unit to its normal or initial position as shown by Figure 1. No other force is brought into play for this purpose.

The axial movement necessary to shift the starting pinion to operative position, shown by Figure 2, is brought about by twin cams 20 of the open crown type and twin studs 21. For manufacturing reasons and to use the factor of inertia most advantageously I prefer to form the cams on the transmission unit and to fix the studs to the shaft so that they will be elements of the operating unit. Furthermore, I prefer to give the sleeve a relatively large diameter in that portion that provides the cam surfaces. The studs may be the end portions of a single piece of rod 30 pressed tightly into a hole extending diametrically through the shaft.

To minimize the lateral strain on the starting shaft 10 developed by the pinion 14 and gear 15 when the starting torque is applied the starting mechanism is so organized that the pinion stands at or near the inboard end of the projecting portion of the shaft, while the cams 20 and studs 21 are located at the outboard end. In other words, the pinion 40 is between the cam mechanism and the bearing 11 and so close to the latter as to receive the maximum bracing effect. Consequently, the outboard end of the shaft extension is relieved from all lateral stress, and accurate meshing of the pinion and gear is assured.

The cam surfaces extend from broken lines *a* beyond broken lines *b* and are concaved and curved. At *a* they are nearly transverse to the axis of rotation, but at *b* the pitch is 50 within the angle of repose. Their curvature develops gradually increasing steepness of pitch from *a* to *b*, and at *b* the pitch is so steep that the studs will not advance farther against the resistance of the spring 16, although the surfaces are continued with increasing steepness a short distance beyond these points to provide a factor of safety. As shown, the cam surfaces have less curvature in the initial stages than in the terminal 60 stages, and therefore have accelerative gradations of pitch steepness.

The studs stand initially at *a*, *a*, where they engage the shoulders 22. When the operating unit is caused to rotate, as by closing a circuit to energize the starting motor,

the studs ride along the cam surfaces, which, in their initial stages, are so nearly at right angles to the axis of rotation that they do not develop enough torque to overcome the inertia of the transmission unit, but develop a powerful end-thrust and relatively slow axial movement of the transmission unit. Before reaching points where the steepness of pitch will develop enough torque to overcome the inertia of the transmission, the pinion will have been shifted into gear and will therefore be restrained from turning until the torque becomes sufficient to start the engine. During the latter stages of shifting the transmission unit the studs encounter the steeper portions of the cams which gradually lose their end thrust and take on the load to be started. The starting torque is thus developed gradually by the cam surfaces until, finally, the studs 21 come to rest at points on the cam surfaces where the inclination is within the angle of repose and is therefore effective to establish a positive transmission. The positive quality is established without imposing any shock on the starting motor or on any part of the mechanism. Furthermore, the axial movement of the transmission unit ceases when the gradually increasing steepness of the cam surfaces 20 and the gradually increasing resistance of the spring 16 have been compounded to a degree sufficient to overcome the resistance of the engine. Even if the engine gear 15 did not turn at all the pins 21 would never reach the steepest parts of the cam surfaces because they continue with increasing steepness beyond the points where the pins are arrested by the spring 16. Thus, in every case the pins advance along the cams only to the points where the starting force is balanced by the engine load and the spring 16, and the construction does not include any shoulder or other positive abutment to arrest the axial movement of the transmission unit. This feature prevents all shock, even in extreme cases as when, for example, the starting motor is arrested by a "backfire" or failure of the engine to respond to the starting force.

The spring 16, in addition to returning the transmission unit to its inoperative position, also modifies the angle of repose of the cam surfaces by bringing about a balance between the torque and the load sooner than if no spring resistance were applied to the transmission unit. As the end-thrust applied by the cam surfaces decreases the counter-thrust applied by the spring increases, but in no case is the end-thrust transmitted to the starting motor when, as shown, the abutment or backing for the spring 16 is provided by a shoulder on the starting shaft 10. According to the construction shown the cam thrust and the counter-thrust of the spring are both sustained by that portion of the shaft between the studs 21 and the shoulder behind the

spring, each phase of the thrust counteracting the other. When the engine starts under an explosive impulse it causes the transmission unit of the starter to overrun the operating unit, whereupon the spring 16 returns the transmission unit to its initial position as shown in Figure 1.

I claim:

1. An engine starter comprising a rotatable and axially movable transmission unit including a starting pinion for engaging and disengaging a gear of the engine, a rotatable operating unit arranged in cooperative relation to said transmission unit, one of said units having a curved cam surface of gradually increasing pitch and the other having means to coact therewith to shift said pinion into gear, and a spring arranged to balance the end-thrust of said transmission unit so that said means will be prevented from advancing to the steepest part of said cam surface.

2. An engine-starter comprising two telescopically related units of which the outer one is supported by the inner one and is provided with a starting pinion, one of said units including a cam and the other including means for coacting with said cam to shift the said outer unit axially and apply the starting torque thereto, and a spring arranged to react on said outer unit to arrest the axial movement thereof and to develop the starting torque gradually to the maximum degree.

3. An engine starter comprising a supporting member having a smooth cylindric external surface, a tubular transmission unit surrounding said supporting member and having a smooth cylindric internal surface bearing thereon and arranged to rotate and slide axially thereon, said transmission unit including a starting pinion for engaging and disengaging a gear of the engine, a spring arranged to urge said transmission unit endwise so as to maintain it normally in an inoperative position, and rotary operating means having diametrically opposite studs projecting radially, said transmission unit having diametrically opposite twin cam surfaces arranged to coact with said studs respectively to shift said transmission unit to an operative position against the applied stress of said spring, said cam surfaces being curved so that the starting action will develop an initially powerful and gradually diminishing end-thrust and a gradually increasing torque.

4. An engine starter comprising a rotary operating unit having a smooth cylindric portion, an axially movable and rotary transmission unit surrounding and supported by said portion so as to slide and turn thereon, said transmission unit including a starting pinion for engaging and disengaging an engine gear, one of said units having a radially projecting cylindric element and the other

having a concave cam surface formed and arranged to coact with said element to shift said transmission unit axially to operative position with gradually increasing speed and torque and with gradually decreasing end thrust, and a spring arranged to arrest axial movement of said transmission unit when said radially projecting element is at an intermediate point of said cam surface.

5. An engine-starter comprising a rotary operating unit, an axially movable transmission unit arranged to slide and turn thereon and having a starting pinion for engaging and disengaging an engine gear, and a spring arranged to oppose with increasing force the axial movement of said transmission unit to starting position, one of said units having a cam surface arranged to cooperate with the other one of said units to shift the transmission unit to starting position against the applied force of said spring, and said cam surface being curved with gradually increasing steepness of pitch beyond a degree sufficient to effect a starting operation.

6. An engine starter comprising a starting shaft provided with diametrically opposite operating lugs, a compression spring surrounding said shaft, an abutment for said spring, and a sleeve interposed between said spring and said lugs and arranged to slide axially on said shaft, said sleeve having a starting pinion and having cam surfaces arranged in cooperative engagement with said lugs, said cam surfaces having relatively gradual inclined portions for shifting said pinion axially to an operating position against the stress of said spring and also having relatively steep inclined portions arranged to transmit the rotation of said lugs to said pinion.

In testimony whereof I have affixed my signature this first day of February, 1922.
